His Attorney.

UNITED STATES PATENT OFFICE

2,091,773

ELECTRIC SOCKET

Fred H. Travers, Stratford, Conn., assignor to
General Electric Company, a corporation of
New York

Application November 20, 1935, Serial No. 50,665

3 Claims. (Cl. 173—330)

The present invention relates to electric sockets of the type adapted for connecting the ground and antenna wires to a radio receiving set.

The object of my invention is to provide an improved construction and arrangement in a socket of this type, and for a consideration of what I believe to be novel and my invention attention is directed to the following description and the claims appended thereto.

10 In the accompanying drawing, Fig. 1 is a top plan view of a socket embodying my invention; Fig. 2 is a side elevation of the socket; and Fig. 3 is an exploded view of the socket.

Referring to the drawing, the socket comprises 15 a receptacle having a housing 1 of insulating material provided with prong receiving openings 2 in the top wall thereof. The bottom of the housing is open and within the housing are suitable arrangements for supporting contacts 3 in line with the prong receiving openings 2. Each of the 20 side walls 4 of the housing is provided with an opening 5 through which connections may be made to the terminals 6 which are integral with the contacts 3. The lower end of the housing 1 is closed by plates 7 which fit within the edges 25 of the housing and rest against suitable shoulders (not shown) adjacent the edges of the housing. The upper and lower plates 7 are made of insulating material, and the intermediate plate 7 is made of steel. These plates therefore form a 30 fire resisting bottom wall for the housing 1.

Below the housing 1 is a housing 8 which is adapted to contain devices, such as a resistance 9 and a condenser 10, which are to be connected to one of the contacts 3. The housing 8, which is made of molded insulating material, is open at the top and is arranged with the edges of its top walls against the lower edges of the housing 1. The resistor and condenser are connected in series and one of the side walls of the housing 8 is provided with a notch 11 through which extends a conductor 12 connected to the free end of condenser 10. From the free end of the resistance 9 extends a conductor 13 which passes through openings 14 in the plates 7 and is connected to one of the terminals 6. With this arrangement, the resistance 9 and condenser 10 and the conductors connected thereto are enclosed within the walls of the housings 1 and 8.

50 The housing 8 is secured to the housing 1 by means of screws 15 which extend through bosses 16 in the housing 8 and through openings 17 in the plates 7. The upper ends of the screws 15 are threaded into openings 18 in ears 19 which are used to mount the socket in a conventional

outlet box. With this arrangement, the screws 15 secure the housings 1 and 8 together and also secure the ears 19 to the top of the receptacle housing. The inner end of the ears 19 fit within recesses 20 in the top wall of the housing 1 and are thereby prevented from turning. The ears are provided with threaded openings 21 by means of which a cover plate may be attached to the receptacle. Depressions 22 are provided beneath the openings 21 into which extend the ends of 10 the screws which attach the cover plate.

After the resistor and condenser, or other devices, have been placed in the housing 8 and the connections made between the devices and the terminals 6 the socket may be assembled by 15 means of the screws 15 and thereafter may be mounted as a unit in the usual outlet box. With this construction, the devices within the housing 8 and the conductors leading therefrom to the terminals 6 are concealed within the walls of the housing. Also, the devices within the housing 8 are further protected by the plates 7. Since 20 the terminals 6 are accessible from the outside of the socket through the openings 5 formed in the side walls of the housing 1, the antenna and ground leads may be attached thereto without 25 disassembling the socket.

What I claim as new and desire to secure by Letters Patent of the United States is:

1. In a socket, a receptacle having a housing of insulating material provided with prong receiving openings in the top and being open at the bottom, contacts carried within said housing, a plate covering the bottom of said housing, a housing adapted to contain a device to be connected to one of said contacts, said housing being open at the top and arranged at the bottom of said receptacle housing with its open end adjacent and closed by said plate, ears for mounting said receptacle in an outlet box, and screws extending through said housings for securing said ears to said receptacle housing and for securing said housings together, and an opening in said plate for the passage of a conductor connecting said device and contact whereby the conductor is concealed within the walls of said housings. 30

2. In a socket, a receptacle having a housing of insulating material provided with prong receiving openings in the top, contacts carried within said housing, terminals connected to said contacts for connecting conductors thereto, said terminals being accessible through the walls of said housing, a plate covering the bottom of said housing, a housing adapted to contain a device to be connected to one of said contacts, said 35

housing being arranged at the bottom of the receptacle housing with its walls abutting the receptacle housing, means for securing said housings together, and an opening in said plate where-
5 by the conductor connecting said device and contact is concealed within the walls of said housings.

3. In a socket, a receptacle having a housing of insulating material provided with prong re-
10 ceiving openings in the top and being open at the bottom, contacts carried within said housing, terminals connected to said contacts for connecting conductors thereto, said terminals being

accessible from the exterior of said housing, a plate covering the bottom of said housing, a housing adapted to contain a device to be connected to one of said contacts, said housing being open at the top and arranged with its open 5 end adjacent and closed by said plate, means for securing said housings together, and an opening in said plate for the passage of a conductor connecting said device and contact whereby the conductor is concealed within the walls of said 10 housings.

FRED H. TRAVERS.
